UNITED STATES PATENT OFFICE

2,436,445

SHOE SEWING MACHINE

Lloyd G. Miller, Beverly, Mass., assignor to
 United Shoe Machinery Corporation, Flemington, N. J., a corporation of New Jersey

Application February 2, 1944, Serial No. 520,767

13 Claims. (Cl. 112—219)

1

This invention relates to shoe sewing machines and is herein illustrated and described as embodied in a machine of the type disclosed in United States Letters Patent No. 1,864,510 granted June 21, 1932, on the application of Bernard T. Leveque. The machine disclosed in said Letters Patent has stitch forming devices that include a high speed reciprocating needle driven through a treadle-controlled mechanism. This mechanism is provided with an element which is movable to disconnect the needle from its actuating mechanism to insure stopping of the needle at the upper end of its stroke regardless of the sewing speed of the machine or of the exact instant at which the treadle is operated with relation to the operating parts. It is desirable in such machines to provide for automatically stopping the needle drive mechanism upon breakage of the thread. However, any control mechanism responsive to the tension on the thread for disconnecting the stitch forming devices upon failure of such tension must have provision for accurate timing of the parts and positive disconnection at high speeds. Also, such a tension control will operate to prevent starting of the machine again unless further provision is made. Furthermore, a mere thread-tension-responsive member would not in itself be sufficient to insure the stopping of the needle in its uppermost position unless timed and connected in the proper manner.

It is an object of the present invention to provide an improved shoe sewing machine having a drive mechanism of the type which is provided with a movable element for disconnecting the actuated device, which is adapted to stop automatically upon breakage of the thread, and which, moreover, is free from the disadvantages above referred to. In accordance with this object, a feature of the machine illustrated herein consists in the provision, in a sewing machine having a Leveque type driving and stopping mechanism, of a means responsive to the loss of tension in the thread for causing the driving and stopping mechanism of the machine to stop the reciprocation of the sewing needle when the thread breaks or becomes slack for any reason. The illustrated machine is further provided with means for rendering the thread-tension-responsive member temporarily inoperative at the beginning of each sewing operation to enable the machine to run until the normal tension in the thread is developed. The illustrated machine is further provided with a means for again rendering the ten-

2

sion-responsive means operative after the normal tension is developed.

These and other features of the machine will appear more fully from the following detailed description when read in connection with the accompanying drawings and will be pointed out in the appended claims.

Referring now to the accompanying drawings:

Fig. 1 is a side elevation of a shoe sewing machine embodying the present invention;

Fig. 2 is an elevation as seen from the opposite side and on a larger scale showing the positions of the various members before the beginning of the sewing operation;

Fig. 3 is a view similar to Fig. 2 showing a portion of the needle driving mechanism during the normal operation of the machine;

Fig. 4 is a view similar to Fig. 3 showing the position of the various members just after the thread has broken but before the drive of the needle has actually been stopped;

Fig. 5 is a sectional view taken on the line V—V of Fig. 2;

Fig. 6 is a plan view in section of a portion of the mechanism shown in Fig. 5;

Fig. 7 is an exploded view of a part of the mechanism shown in Fig. 6; and

Fig. 8 is a sectional view taken on the line VIII—VIII of Fig. 2.

The supporting structure of the illustrated machine consists of a hollow frame or housing 10. The operating instrumentalities, as shown in Fig. 1, consist of a needle 12 (see also Fig. 2), a rotary loop-taker 13, and a pair of upper and lower feed rolls 14 and 16, respectively, which grip between their peripheral surfaces the marginal portions of the upper and sole of a stitchdown shoe. The needle 12 is supplied with thread T which comes from a reel (not shown) and which passes over an adjustable tensioning device 18, over a pull-off 20, through a thread lock 22 for preventing reverse movement of the thread, over a lubricating roll 24, and past a take-up 26 on its way to the needle. The needle is actuated through a train of mechanism comprising an element relatively movable to disconnect the needle from the driven parts of the mechanism. As disclosed in the patent to Leveque No. 1,864,510, above mentioned, the take-up and the feed rolls are also driven through said disconnectible element.

The machine is driven through a belt 28 from any suitable source of power. The belt 28 drives a pulley 30 which, through a clutch 32, may be coupled at will to a shaft 34 which is the main sewing shaft. The clutch 32 is actuated through

a yoke 36 and treadle rod 38 by a treadle 40 which is normally held up by a spring 42. Depression of the treadle 40 effects a coupling movement of the clutch members and starts the drive of the shaft 34.

The needle 12 is carried by a needle bar 44 which reciprocates in a vertical guideway formed in the frame 10. Clamped on the needle bar 44 is a collar 48 having a lug 46 to which is pivotally connected the upper end of a link 50. The lower end of the link 50 is pivotally connected to a forwardly extending arm 52 of a driving bell crank 54 having a downwardly extending arm 56. The bell crank 54 is fulcrumed upon a horizontal stud 58 having a reduced threaded end 60, best shown in Figs. 5 and 8. A nut 62 threaded upon the end 60 clamps a shoulder of the stud 58 against a boss 64 extending inwardly from the wall of the frame 10. A driven bell crank 66 also fulcrumed upon the stud 58 has a rearwardly extending arm 68 and a downwardly extending arm 70. A collar 69 (Figs. 3 and 8), secured by a setscrew 11 to the free end of the stud 58, retains the two bell cranks upon the stud. When the machine is to be driven, the depending arms 56 and 70 of the two bell cranks are latched together by a mechanism later to be described, causing the two bell cranks to function as a single lever. Pivotally connected to the rearwardly extending arm 68 by a ball joint 72 is a connecting rod 74, the lower end of which carries a bearing 76 which is mounted upon a crank 18 on the main shaft 34. Rotation of the shaft 34 operates through the crank and connecting rod above mentioned to rock the arms 68 and 52 (provided the two bell cranks are coupled) and thereby to reciprocate the needle bar.

The mechanism for coupling and uncoupling the bell cranks 54 and 66 to connect or disconnect the needle from its actuating mechanism will now be described. Rotatable in a sleeve 79 (Fig. 8) carried by the depending arm 56 is a pivot pin 80 upon one end of which is mounted a hook-shaped disconnecting latch 82 which is engageable with a pin 84 extending from the depending arm 70. The sleeve 79, which is not shown in Figs. 2, 3 and 4, is of the same diameter and is directly in back of the hub of the latch 82, shown in those figures. When the latch 82 engages the pin 84, as shown in Fig. 1, the two bell cranks are coupled together to move as a unit, a pair of co-engaging lugs 86 and 88 on the respective bell cranks being brought into contact at the same time. Secured upon the other end of the pin 80 is a hub 99 (Fig. 8) having an arm 91 to which is attached one end of a tension spring 90, tending to urge the latch 82 into engagement with the pin 84. In order to provide for unhooking the latch 82 and uncoupling the bell cranks, the latch 82 is provided with a tail 94 which may be engaged by a pin 96 carried by an arm 98 to rock the latch into uncoupling position, as shown in Fig. 2. The machine as so far described is similar in all respects to that disclosed in the above-mentioned patent to Leveque.

In the machine of the Leveque patent, the arm corresponding to the arm 98 is made fast to a rockshaft extending through a bearing in the side of the machine frame and having rigidly secured to it a treadle-controlled arm. The arm corresponding to the arm 98, therefore, is actuated positively by treadle-controlled connections

to unhook the latch or to cause the latch to connect the bell cranks 54 and 66.

In the machine embodying the present invention, the treadle 40 is connected through a releasable joint with the latch 82 in such a way that upon the occurrence of slack or broken thread, even though the treadle is held in depressed position, the driving and driven bell cranks 66 and 54 may be uncoupled. For this purpose a sewing-thread-tension-responsive member is provided for rendering the treadle ineffective to cause the latch to be held in latching relation with the pin 84. The connections and the releasable joint are constructed in a novel and effective manner to prevent the machine from being restarted until the treadle is released and again depressed and suitable additional mechanism also is provided for rendering the thread-tension-responsive member temporarily inoperative at the beginning of a new seam so that proper sewing operations may be performed in spite of the existence of slack thread.

The connections between the latch actuating arm 98 and the treadle are best illustrated in Figs. 5, 6 and 7 and include a hub 99 from which the arm 98 projects, a horizontal rockshaft 100 on which the hub 99 is mounted for free rotation, a split collar 104 secured upon the inner end of the rockshaft 100 by a clamping screw 103 for maintaining the hub 99 in position upon the shaft, a hub 106 secured upon the shaft 100 by a clamping screw 104, and other connections to be described hereinafter. The rockshaft 100 is journaled in a bearing 102 which is integral with the side wall of the housing 10.

Formed in one of the end faces of the hub 106 is a notch 108 into which extends a tongue 110 from the hub 99. The width of the tongue 110 circumferentially with respect to the axis of the shaft 100 is less than the width of the notch 108 to afford the arm 98 a limited amount of lost motion with respect to the hub 106 and therefore with respect to the shaft 100. A torsion spring 112 wrapped around the hub 106 has one end hooked about a pin 114 secured in the hub 106 and its opposite end bearing against the arm 98 to urge the arm 98 downwardly as far as permitted by the tongue 110.

The releasable joint in the treadle connections is mounted on the right end of the shaft 100, which extends outside of the housing 10. The joint comprises a wedge-shaped cam 120 and a spring-pressed plunger 128. The cam 120 is carried by a collar 118 secured to the shaft 100 by a setscrew 116. The plunger 128 is slidably mounted in a treadle-controlled arm 124. This plunger consists of a shank 127 (Figs. 4 and 5) and a wedge-shaped outwardly extending end which yieldingly engages the cam 120 under the influence of a compression spring 130. The shank 127 is grooved to engage a pin to prevent turning of the shank. Freely rotatable upon the shaft 100 between the bearing 102 and the collar 118 is a hub 122 of the arm 124, the rear end of which is pivotally connected to a sleeve 126 threaded for purposes of adjustment upon the upper end of the treadle rod 38. It is evident that depression of the treadle will lower the arm 124, rocking it in a counterclockwise direction, as seen in Fig. 2, and thereby, through the engagement of the detent 128 with the cam 120, will rock the shaft 100 to raise the arm 98 and permit the latch 82, under the influence of the spring 90, to engage the pin 84 and thereby start reciprocation of the needle 12. Likewise, when the operator allows

the treadle 40 to rise, the arm 98 will descend and the pin 96 will engage the tail of the latch 82 to uncouple the latch. However, as is shown in Figs. 3 and 4, the arm 98 has formed in it a notch 132 which receives the sleeve 79 and, until this sleeve is moved into a position wherein it can enter the notch 132, the arm 98 will be held up by the engagement of its lower edge with the sleeve. The purpose of the torsion spring 112 and the provision of lost motion between the recess 108 and the tongue 110 is to enable the arm 98 thus to be yieldingly held up until the needle reaches the highest point of its travel, at which time the sleeve 79 will be directly below the notch 132 and the arm 98 will thereupon drop into position for disengaging the drive of the needle.

The mechanism for rendering the releasable joint ineffective and for stopping reciprocation of the needle in case the thread breaks will now be described. It comprises a thread engaging tension-responsive roll 136 freely rotatable upon a shaft 138 carried by the upper end portion of a rod 140 which extends downwardly through a bearing 142 formed in the top wall of the housing 10. The roll 136 is urged upwardly by a compression spring 144 surrounding the rod 140 interposed between the bearing 142 and collar 146 secured on the rod 140. The lower end of the rod 140 is pivotally connected to an arm 148 of a bell crank 150 having a hub which is free to rock upon a stationary pin 141 secured in the housing 10. A downwardly extending arm 152 of the bell crank 150 is pivotally connected to one end of a link 154. A stationary pin 158, secured in the housing 10, engages the arm 152 to limit upward movement of the rod 140 under the influence of the spring 144. The opposite end of the link 154 is pivotally connected to a push rod 156 which is supported on a pin 158 secured in an arm 160 extending from the hub 106. To actuate the push rod upon loss of thread tension, the bell crank 54 has a pin 162 which, in the course of its downward oscillating movement, may or may not engage the free end of the rod 156, according to the positions of the tension-responsive roll 136 and the rod 156. During the normal running of the machine the tension of the thread T holds the roll 136 down low enough (as shown in Fig. 3) to keep the rod 156 out of the path of the pin 162. However, if the thread should break, the spring 144 will raise the arm 140 and rock the bell crank 150 in a clockwise direction and thereby, through the link 154, will swing the rod 156 upwardly a short distance in a counterclockwise direction. Then the pin 162, upon its next downward movement, will strike the end of the rod 156 and will operate, through the rod 156, to rock the arm 160 and thereby the hub 106 in a clockwise direction to cause the arm 98 to drop into uncoupling position as soon as the needle reaches the top of its stroke. While the shaft 100 will turn with the hub 106, the detent 128 will yield to avoid transmitting any shock to the operator through the treadle. Fig. 4 shows the position of the parts after the thread has broken or become slack. The rod 156 has just received a downward thrust from the pin 162. This downward thrust has caused the shaft 100 to turn in a clockwise direction, raising the cam 120 up past the yielding detent 128. The arm 98 will now drop as soon as the bell-crank arm 56 completes its stroke to the right.

The operator will, of course, when he sees that reciprocation of the needle has stopped, release the treadle and stop the transmission of power

through the clutch 32. As the treadle rises, the detent 128 will slip up over the cam 120 to its normal position (as shown in Figs. 2 and 3).

However, in order to permit the starting of the machine after the operator has rethreaded the needle, the roll 136 must be lowered from its raised position, otherwise the releasable joint will again be rendered ineffective and needle reciprocation stopped. To this end, there is provided a latch 182 which is freely pivoted upon a horizontal pin 184 extending inwardly from the arm 124 and passing through an opening 186 (see Fig. 5) formed in the wall of the housing 10. A torsion spring 188 urges the latch 182 in a clockwise direction, as seen in Figs. 2, 3 and 4. Formed on the upper portion of the latch 182 is a hook 189 (Figs. 3 and 4) which, as shown in Fig. 2, engages the free end of the arm 148 so as to be able to draw the arm downwardly when the treadle is later depressed. Such movement of the arm 148 acts through the link 154 to swing the rod 156 out of the path of the pin 162, thus preventing the releasable joint from being disconnected. However, the tension-responsive roll 136, as long as it is held down positively by the latch 182, is unable to perform its function.

In order to restore the thread-tension-responsive roll 136 to operative condition there is provided a rod 190 pivotally connected at one end to the bell crank 54 and having its opposite end free. The rod 190 is supported by a guide 192 which, for convenience, is carried by the bell crank 150, the guide 192 having an eye through which the rod 190 is freely slid able. As soon as the operation of the machine begins, the bell crank 54 will be rocked to move the needle down and, in the course of this movement, it will force the rod 190 to the left, as seen in Figs. 2, 3 and 4. The free end of the rod 190 will thereupon strike 40 against a surface 194 on the latch 182 and swing the latch to the left, thereby releasing the arm 148 and permitting the roll 136 to rise to its normal operating position, as shown in Fig. 3.

Certain members of the mechanism for actuating the sewing thread pull-off 20 shown in the drawings (and not yet mentioned) are like corresponding members disclosed in the above-mentioned patent to Leveque. These members are shown herein because they are carried by or connected to portions of the mechanism which embody the present invention, and their illustration simplifies and renders obvious the relation of the mechanism of the present invention to the complete machine disclosed in the patent to Leveque. The particular members in question are as follows: an arm 170 extending rearwardly from the hub 106 and serving, through a link 172, to operate a lever 180 which carries the pull-off 20.

The general operation of the machine will be apparent from the foregoing description and reference to the Leveque patent. The machine is shown in Fig. 2, after stopping by release of the treadle, in a position of rest with the arm 143 in its up position but engaged positively by the latch 182, the treadle and the latch 182 being also in their up position. The operator depresses the treadle to start the machine and as the treadle is depressed the latch 182 and the roll 136 will be drawn down with it. After the first stitch the latch is released by the rod 190 and the roll 136 becomes operative, as shown in Fig. 3. If the thread breaks, the release of its tension against the roll 136 causes the spring 144 to raise the rod 140, thereby swinging the arm 156 in a counterclockwise direction from the position shown in

Fig. 3 to the position shown in Fig. 4. The pin 162, thereupon, on the next downward stroke of the needle, engages the end of the arm 155 and causes the rockshaft 100 to rotate in a clockwise direction. The latch actuating arm 28, upon the next upward stroke of the needle, will then upon descend and release the latch 162 from the pin 164 and stop reciprocation of the needle with the needle at its highest point. The operator may then rethread the needle or otherwise adjust the machine and continue in the manner already described.

Having described my invention, what I claim as new and desire to secure by Letters Patent of the United States is:

1. In a sewing machine, the combination with stitch forming devices, a main sewing shaft and trains of driving mechanism for actuating the stitch forming devices from the sewing shaft, at least one of said trains of mechanism comprising coupling elements relatively movable to connect one of the actuated devices to and disconnect it from the shaft, and yielding depressible treadle connections acting when depressed to cause the coupling elements to be held in connecting relation, of means responsive to tension on the sewing thread for rendering the treadle connection ineffective to cause the coupling elements to be held in connecting relation.

2. In a sewing machine, the combination with stitch forming devices, a main sewing shaft and trains of driving mechanism for actuating the stitch forming devices from the sewing shaft, at least one of said trains of mechanism comprising coupling elements relatively movable to connect one of the actuated devices to and disconnect it from the shaft, yielding depressible treadle connections acting when depressed to cause the coupling elements to be held in connecting relation, and a sewing-thread-tension-responsive member, of a releasable joint connecting the treadle connections with the coupling elements of the driving mechanism constructed and arranged to be released by actuation of the tension-responsive member under loss of thread tension and rendered ineffective to cause the coupling elements to be held in connecting relation while the treadle connections are maintained in depressed position.

3. In a sewing machine, the combination with stitch forming devices, a main sewing shaft and trains of driving mechanism for actuating the stitch forming devices from the sewing shaft, at least one of said trains of mechanism comprising coupling elements relatively movable to connect one of the actuated devices to and disconnect it from the shaft, yielding depressible treadle connections acting when depressed to cause the coupling elements to be held in connecting relation, a sewing-thread-tension-responsive member, and a releasable joint connecting the treadle connections with the coupling elements of the driving mechanism, of mechanism actuated by the thread tension responsive member to release the joint connecting the treadle connections with the coupling elements of the driving mechanism upon loss of thread tension.

4. In a sewing machine, the combination with stitch forming devices, a main sewing shaft and trains of driving mechanism for actuating the stitch forming devices from the sewing shaft, at least one of said trains of mechanism comprising driving and driven parts and coupling elements relatively movable to connect and disconnect said parts, yielding depressible treadle connections acting when depressed to cause the coupling ele-

ments to be held in connecting relation, a sewing-thread-tension-responsive member, and a releasable joint connecting the treadle connections with the coupling elements of the driving mechanism, of normally inoperative means actuated by the driven part of the driving mechanism for releasing said joint to disconnect the driving and driven parts when the responsive member is actuated by loss of thread tension.

5. In a sewing machine, the combination with stitch forming devices, a main sewing shaft and trains of driving mechanism for actuating the stitch forming devices from the sewing shaft, at least one of said trains of mechanism comprising driving and driven parts and a coupling element relatively movable to connect and disconnect said parts, yielding depressible treadle connections acting when depressed to cause the coupling element to be held in connecting relation, a sewing-thread-tension-responsive member, a releasable joint connecting the treadle connections with the coupling element of the driving mechanism, and normally inoperative means actuated by the driven part of the driving mechanism for releasing said joint to disconnect the driving and driven parts when the responsive member is actuated by loss of thread tension, of means for maintaining said releasing means inoperative for a brief period after the treadle connections have again been depressed to enable the driving and driven parts of said train of mechanism to remain connected notwithstanding the initial lack of tension in the sewing thread.

6. In a sewing machine, the combination with stitch forming devices, a main sewing shaft and trains of driving mechanism for actuating the stitch forming devices from the sewing shaft, at least one of said trains of mechanism comprising driving and driven parts and a coupling element relatively movable to connect and disconnect said parts, yielding depressible treadle connections acting when depressed to cause the coupling element to be held in connecting relation, a sewing-thread-tension-responsive member, a releasable joint connecting the treadle connections with the coupling element of the driving mechanism, normally inoperative means actuated by the driven part of the driving mechanism for releasing said joint to disconnect the driving and driven parts when the responsive member is actuated by loss of thread tension, and means for preventing said tension responsive member from actuating said releasing means after the treadle connections have again been depressed to enable the driving and driven parts of said train of mechanism to remain connected notwithstanding the initial lack of tension in the sewing thread, of means actuated by the driven part of the driving mechanism for rendering inoperative said preventing means and thereby enabling said tension-responsive means to control the drive of said driven part.

7. In a sewing machine, sewing instrumentalities, driving mechanism, a latch through which the drive of said driving mechanism is transmitted to said sewing instrumentalities, operator-controlled means for connecting and disconnecting said latch to start and stop the transmission of drive to the sewing instrumentalities at will, means responsive to the tension of the thread operated upon by the machine for disconnecting said latch when the thread breaks, and means for rendering said tension-responsive means temporarily inoperative after said latch has again been connected by said operator-controlled

means, thereby enabling the machine to run until tension develops in the thread.

8. In a sewing machine, sewing instrumentalities, driving mechanism, a latch through which the drive of said driving mechanism is transmitted to said sewing instrumentalities, operator-controlled means for connecting and disconnecting said latch to start and stop the transmission of drive to the sewing instrumentalities at will, means responsive to the tension of the thread operated upon by the machine for disconnecting said latch when the thread breaks, means for rendering said tension-responsive means temporarily inoperative after said latch has again been connected by said operator-controlled means, thereby enabling the machine to run until tension develops in the thread, and means operated by said sewing instrumentalities after said latch has been connected for rendering said tension-responsive means operative.

9. In a sewing machine, sewing instrumentalities, driving mechanism, a latch through which the drive of said driving mechanism is transmitted to said sewing instrumentalities, a device engageable with the thread operated upon by the machine, said thread-engageable device being constructed and arranged to perform yieldingly an operative movement upon relaxation of the tension of the thread by breakage thereof, means operated by said device for disconnecting said latch to stop the drive of the sewing instrumentalities when the device performs its operative movement, and a latch for holding said device against said operative movement to enable the machine to start running again regardless of the tension of the thread.

10. In a sewing machine, a needle bar for holding a needle to which a thread is supplied, an oscillatory driving member, connections between said driving member and said needle bar for driving the needle bar in synchronism with the movements of the driving member, a releasable coupling in said driving connections, and tension-responsive means controlled by said thread for releasing said coupling and thereby stopping the drive of said needle bar upon breakage of the thread.

11. In a sewing machine, a needle bar for holding a needle to which a thread is supplied, an oscillatory driving member, connections between said driving member and said needle bar for driving the needle bar, a releasable coupling in said

driving connections, movable means for releasing said coupling to disconnect the needle bar from the driving member, means for holding said releasing means from operative movement to disconnect the needle bar until the needle bar reaches a predetermined position in its stroke, and tension-responsive means controlled by said thread for yieldably urging said releasing means into operative position to cause the releasing means to disconnect the needle bar from the driving member as soon as the needle bar reaches said predetermined position.

12. In a sewing machine, a needle bar for holding a needle to which a thread is supplied, an oscillatory driving member, connections between said driving member and said needle bar for driving the needle bar, a releasable coupling in said driving connection, tension-responsive means controlled by said thread for releasing said coupling and thereby stopping the drive of said needle bar upon failure of tension resulting from breakage of the thread, and means for preventing operation of said releasing means when the machine is started again until tension has developed in the thread.

13. In a sewing machine, a needle bar for holding a needle to which a thread is supplied, an oscillatory driving member, connections between said driving member and said needle bar for driving the needle bar, a releasable coupling in said driving connections, tension-responsive means controlled by said thread for releasing said coupling and thereby stopping the drive of said needle bar upon failure of tension resulting from breakage of the thread, means for preventing operation of said releasing means when the machine is started, and means operated by said connections on the driven side of said coupling for rendering the preventing means inoperative and thereby rendering the releasing means operative after movement of the needle bar has started again.
